UNITED STATES PATENT OFFICE.

JOHN BEISWANGER, OF STEUBENVILLE, OHIO, ASSIGNOR TO GILL BROTHERS COMPANY, OF STEUBENVILLE, OHIO, A CORPORATION OF WEST VIRGINIA.

DESIGN FOR A SQUARE CASSEROLE.

57,182.

Specification for Design.

Patented Mar. 1, 1921.

Application filed October 31, 1919. Serial No. 334,862. Term of patent 14 years.

To all whom it may concern:

Be it known that I, JOHN BEISWANGER, a citizen of the United States of America, and resident of Steubenville, county of Jefferson, State of Ohio, have invented a certain new, original, and ornamental Design for a Square Casserole, of which the following is a specification.

In the accompanying drawing I have illustrated a square casserole, constructed in accordance with my invention, the same being of resistive transparent glass.

Figure 1 is a perspective view of the square casserole showing my new design.

Fig. 2 is a bottom plan view.

Having thus described and illustrated my invention, I claim:

The ornamental design for a square casserole, substantially as shown.

Signed by me at Steubenville, Jefferson county, Ohio, this 22nd day of October, 1919.

JOHN BEISWANGER.
